UNITED STATES PATENT OFFICE.

J. S. SAMMONS, OF NEW YORK, N. Y.

MODE OF ROOFING WITH SLATE.

Specification of Letters Patent No. 32,383, dated May 21, 1861.

To all whom it may concern:

Be it known that I, J. S. SAMMONS, of the city, county, and State of New York, have invented a new and useful Improvement 5 in Roofing with Slate; and I do hereby declare that the following is a full, clear, and exact description of the same, reference being had to the annexed drawings, making a part of this specification, in which—

Figure 1, is a plan or top view of a section of a roof with the slate laid according to my invention. Fig. 2, a section of the same, taken in the line x, x , Fig. 1. Fig. 3, an enlarged section of the same, taken in the 15 same line as Fig. 2.

Similar letters of reference indicate corresponding parts in the several figures.

Various plans have been devised for laying slate roofs in order to overcome two 20 difficulties; 1st, the breaking or fracturing of the slate in winter, due to the freezing of the water which lodges in the interstices, and 2nd, the sagging or settling of the roof, and consequent parting of joints and leakage, a result due to the weight of the slate. The first mentioned difficulty has been partially overcome by laying the slate in cement, without lapping the slabs, thereby allowing no joints or interstices for water to 25 lodge in. The second difficulty however has not, so far as I am aware, been hitherto obviated. The slate when first laid in the ordinary way makes an exceedingly tight roof, the cements that are used forming 30 water-tight joints but inelastic or unyielding one and consequently on the sagging or settling of the roof, which soon occurs, the joints crack, or rather the cement, and the roof is not weather proof.

The object of this invention is to obviate 40 these difficulties and to this end I form elastic joints substantially as hereinafter described, whereby the joints are allowed to yield or give to compensate for the sagging or settling of the roof and at the same time remain perfectly water tight.

To enable those skilled in the art to fully understand and construct my invention I will proceed to describe it.

The rafters of the roof are covered with 50 boards or planks A. as usual, and the slate slabs B. laid directly thereon. These slabs may be of any desired dimensions, but a square foot would probably be the most desirable size. These slabs are dressed or got

out so as to have parallel sides and ends, and the edges of the slabs are ground beveling at their top and bottom as shown at a, a , in Figs. 2 and 3. By thus forming the edges of the slabs they are not liable to chip off in handling or in transporting them from place to place, as obtuse angles b , are formed at the edges of the slabs.

Each slab B. has a hole made through its center. These holes are counter-sunk to receive the heads of the screws c, by which the slabs are secured to the boards or planks A.

The slabs A. are laid as follows. The first slab is laid on the boards or planks and secured thereto by its screw c, and the under 70 or lower edge of the slab is then coated with a solution of india-rubber, and a strip C. of india rubber is then placed against the under or lower edge of the said slab, the solution of rubber connecting it to the slab. The 75 succeeding slab A. is then placed against the rubber strip C., the edge of the latter slab being coated with the india rubber solution, and pressed against the rubber so that it will fill the lower part of the space between the 80 slabs, and the second slab is then secured to the boards or planks by its screw c. The slabs are thus laid one after the other until one row the whole length of the roof is completed, and a second row is then laid adjoining the first, india-rubber strips being interposed between the rows, or at the sides of the slabs as well as at their upper and lower ends. The former strips however may be 85 of any length, the whole length or depth of 90 the row if desired, while the rubber strips C. are equal in length to the width of the slabs.

The rubber strips C. do not entirely fill the spaces between the slabs A. the strips C. extending upward about as far as the lower 95 edges of the upper beveled surfaces a , as shown clearly in Figs. 2 and 3.

The space above the rubber strips C. is filled with a cement D. composed of coal tar, a solution of india rubber, gutta percha, and a mineral compound known as Prince's paint. The ingredients above named are placed into a proper vessel and heated over a fire to insure a proper amalgamation and the cement may be applied by means of a 100 brush either in a warm or cool state, the cement gradually hardening by age. After the cement D. is applied it may be coated with sand d.

The cement D. serves to protect the india- 110

rubber strips C. and at the same time it is sufficiently yielding to give to the sagging of the roof without cracking. The india rubber strips C. below the cement D. will of course yield more than the cement and it is necessary that they should, for the rubber, as the roof sags, will be more distended than the cement.

10 The heads of the screws *c*, extend sufficiently far into the counter sinks of the slabs to permit of the heads being covered by cement D.

15 I do not claim broadly the laying of slate slabs with cement, for that has been previously done, nor do I claim separately or in itself considered any of the parts herein described, but

I do claim as new and desire to secure by Letters Patent,

The laying of the slate slabs B. on the 20 planks or boards A. with strips C. of india-rubber interposed between them, and secured thereto by a solution of india-rubber; in connection with the cement D. placed over the rubber strips C. and completely filling 25 the interstices between the slate slabs while the latter are permanently secured in position by the screws *c*, substantially as described.

J. S. SAMMONS.
